VERTICALLY DISCHARGING BLADE DISPENSER

Zemach Auerbach, Bronx, N. Y.; Philip R. Auerbach, administrator of the estate of said Zemach Auerbach, deceased

Application November 27, 1948, Serial No. 62,260

8 Claims. (Cl. 30—40)

1

This invention relates to a dispenser for safety razor blades and more particularly has reference to a dispenser of the said type wherein a stack of razor blades may be housed, razor blades singly released therefrom and deposited directly in its seat upon a conventional safety razor.

An object of this invention is the means provided therein for singly depositing a safety razor blade upon a conventional safety razor without the fingers of the hand contacting the blades during the said action.

Another object of this invention is the provision therein of means for singly discharging safety razor blades from the dispenser to its seat upon a double shutter type razor or upon a razor blade holder block of a regulation disassembled razor.

A further object of this invention is the inclusion therein of a finger manipulated slider element which is formed from a single sheet of material, which slider element is provided to hold the said stacked razor blades in place within the dispenser and also adapted by successive reciprocal sliding movements to discharge a single safety razor blade at the end of each reciprocal movement.

A still further object of this invention is the provision of an organization in which the constituent elements are so arranged structurally and functionally as to assure improved results with materials and members which may be manufactured at reasonable cost, may be easily assembled and which will be efficient in operation with minimum wear to the parts.

The best embodiment of the invention has been chosen for illustrative purposes, but this embodiment should be viewed as being illustrative only and not as limiting because obviously the invention is capable of other embodiments having revised details of construction, so long as they fall within the ambit of the appended claims.

The invention itself, however, both as to its organization and its method of operation, will best be understood from the following description of a specific embodiment when read in connection with the accompanying drawings, in which:

Fig. 1 is a top view of the dispenser.

Fig. 2 is a bottom view thereof.

2

Fig. 3 is a side elevational view of the same, Fig. 4 is an end view of same.

Fig. 5 is a transverse section, in elevation, taken along line 5—5 of Figs. 1 and 2.

Fig. 6 is a longitudinal sectional view, in elevation, taken along line 6—6 of Fig. 1.

Fig. 7 is a view of a safety razor blade having a central cut out portion to conform to this invention.

Fig. 8 is a similar view but shows a reverse arrangement of the central cut out portion shown in Fig. 1.

Fig. 9 is a side elevational view of the slider element forming a part of this invention.

Fig. 10 is an end view of same.

Fig. 11 is a plan and side view of a spring element employed in said invention.

Referring in detail to the parts (Figs. 1 to 11 inclusive), 11 designates a housing comprising

a top plate 12 formed with end walls 13, side walls 14, a central opening 15 and a longitudinally disposed slot 16. The side walls 14 are formed with inwardly turned ends 17 and the said end walls 13 are formed with inwardly turned ends 18.

The said side walls 14 and the inwardly turned ends 17 providing recesses to receive the long or side edges 19 of a razor blade 20, while the corners formed at 18 with the end walls 13 provide recesses to receive the projecting end portions 21 of said razor blades 20.

The said razor blades are of conventional type with the exception of a central cut out portion in the shape of a rectangular opening 22 having notches 23 at one end thereof. The said notches

23 are adapted to receive ledge formations 24 formed upon the lower ends of depending legs 25 in turn formed upon a slider element 26. The said slider element 26 is adapted to reciprocal sliding movement upon the top plate 12 of the said housing and is guided in its movement thereupon by depending lugs 27 formed upon the said slider element 26 and engaging in the said slot 16.

The razor blades 20 are stacked within the said housing 11 (Figs. 2, 5 and 6) the lowermost blade designated as 28, being held within said housing by the said lugs 24 while a U-shaped spring element 29, formed with legs 30 (Fig. 11)

is disposed between the top plate 12 of the said housing 11 and the uppermost razor blade to urge the lowermost blade in close contact with

the said lugs 24. The said blades are arranged, when packed within the said housing, so that they lie in alternate reverse order, thereby aligning the said notches 24 in staggered vertical relation to one another.

When the said slider 26 is moved to one extreme position (Fig. 2) the lugs 24 engage over the sides of the said rectangular opening 22 in the blade and hold same and all the blades stacked above it in place within the housing. When, however, the slider 26 is moved to its opposite extreme position, the lugs 24 of said slider 26 will align with the notches 23 of the contacting razor blade 28 and allow same to drop from the housing to a conventional razor 32 of the double shutter type hereinbefore mentioned and shown in Fig. 6. The following blade, obviously, is held within the said housing against displacement. End walls 31 are formed upon the said slider 26 to provide a finger contact thereon.

The spring shown in Fig. 11 is preferably formed of spring wire but a spring of a flat metal strip may be employed.

Referring to the housing shown in Fig. 1, in place of the spring shown in Fig. 11, the top 12 may be slotted, to form inwardly bent spring members which holds the stack of blades within the housing under downward pressure.

I claim:

1. A bottomless dispenser for stacked razor blades comprising a top, sides and ends, an opening in said top, a blade retaining member within said opening, said opening guiding and limiting the movement of said blade retaining member, said blade retaining member having legs and ledges at the ends of said legs for holding and releasing said blades singly by manual movement of said blade retaining member and said blade retaining member releasing a single blade from the bottom of said stack of blades upon movement of said blade retaining member from one side of said top opening to the opposite side of said top opening.

2. A bottomless dispenser for stacked razor blades comprising a top, sides and ends, an opening in said top, a blade retaining member within said opening, said opening guiding and limiting the movement of said blade retaining member, said blade retaining member having legs and ledges at the ends of said legs for holding and releasing said blades singly by manual movement of said blade retaining member, said blade retaining member releasing a single blade from the bottom of said stack of blades upon movement of said blade retaining member from one side of said top opening to the opposite side of said top opening, and a spring between said top and said blades holding said stack of blades in said dispenser under pressure permitting the lowermost blade to be released under force.

3. A bottomless dispenser for stacked razor blades comprising a top, sides and ends, an opening in said top, a blade retaining member within said opening, said opening guiding and limiting the movement of said blade retaining member, said blade retaining member having legs and ledges at the ends of said legs for holding and releasing said blades singly by manual movement of said blade retaining member, said blade retaining member having a central opening to receive the central post of a razor cap and finger pieces for sliding said member back and forth and said blade retaining member releasing a single blade from the bottom of said stack of

blades upon movement of said blade retaining member from one side of said top opening to the opposite side of said top opening.

4. A bottomless dispenser for stacked razor blades comprising a top, sides and ends, an opening in said top, a blade retaining member within said opening, said opening guiding and limiting the movement of said blade retaining member, said blade retaining member having legs and ledges at the ends of said legs for holding and releasing said blades singly by manual movement of said blade retaining member, inwardly formed portions on said ends for centrally retaining said stack of blades within said dispenser and said blade retaining member releasing a single blade from the bottom of said stack of blades upon movement of said blade retaining member from one side of said top opening to the opposite side of said top opening.

5. A bottomless dispenser for stacked razor blades comprising a top, sides and ends, an opening in said top, a blade retaining member within said opening, said opening guiding and limiting the movement of said blade retaining member, said blade retaining member having legs and ledges at the ends of said legs for holding and releasing said blades singly by manual movement of said blade retaining member, inwardly formed portions on said sides for aligning said dispenser upon a razor and said blade retaining member releasing a single blade from the bottom of said stack of blades upon movement of said blade retaining member from one side of said top opening to the opposite side of said top opening.

6. A bottomless dispenser for stacked razor blades comprising a top, sides and ends, an opening in said top, a blade retaining member within said opening, said opening guiding and limiting the movement of said blade retaining member, said blade retaining member having legs and ledges at the ends of said legs for holding and releasing said blades singly by manual movement of said blade retaining member, inwardly formed portions on said ends for centrally retaining said stack of blades within said dispenser, inwardly formed portions on said sides for aligning said dispenser upon a razor and said blade retaining member releasing a single blade from the bottom of said stack of blades upon movement of said blade retaining member from one side of said top opening to the opposite side of said top opening.

7. A bottomless dispenser for stacked razor blades comprising a top, sides and ends, an opening in said top, a blade retaining member within said opening, said opening guiding and limiting the movement of said blade retaining member, said blade retaining member having legs and ledges at the ends of said legs for holding and releasing said blades singly by manual movement of said blade retaining member, said sides having opposed shoulders for aligning said dispenser upon a razor cap, and said blade retaining member releasing a single blade from the bottom of said stack of blades upon movement of said blade retaining member from one side of said top opening to the opposite side of said top opening.

8. A bottomless dispenser for stacked razor blades comprising a top, sides and ends, an opening in said top, a blade retaining member within said opening, said opening guiding and limiting the movement of said blade retaining member, said blade retaining member having legs and ledges at the ends of said legs for holding and releasing said blades singly by manual movement of said blade retaining member, said blade re-

taining member having a central opening to receive the central post of a razor cap and finger pieces for sliding said member back and forth, inwardly formed portions on said ends for centrally retaining said stack of blades within said dispenser, said sides having opposed shoulders for aligning said dispenser upon a razor cap and said blade retaining member releasing a single blade from the bottom of said stack of blades upon movement of said blade retaining member from one side of said top opening to the opposite side of said top opening.
